ABSTRACT OF THE DISCLOSURE

The code translator is of the mechanical power driven type having a cycle-control clutch which is controlled to initiate each new translator cycle and during which a plurality of code permutation slides are set to permutational positions according to individual ones of the code elements in each of successive multiple code-element permutation electrical codes supplied to the translator. A plurality of translator seekers test each such permutational slide setting and are individually selected thereby for power drive actuation of a corresponding typewriter key lever to print successive alphanumeric and symbol characters during each of successive translator cycles and at a cyclic rate higher than the repeat-character printing rate of the typewriter. An electrical storage register, which may be of the bistable multivibrator or core storage type, stores during an interval following completion of each translator cycle the binary-zero and binary-one code bits of the permutation code supplied to the translator during such each translator cycle. This stored code is compared with the next code supplied to the translator to ascertain whether such next code is identical to or is different from the stored code. If the comparison shows a code difference, the translator cycle-control clutch is so controlled as to initiate a translator cycle of operation concurrently with supply of the new code to it. If the comparison shows code identity, the translator cycle of operation is delayed in its initiation by the cycle-control clutch or is prolonged by clutch-controlled halt of the translator at an intermediate cyclic position. This reduces the operating rate of the translator to the repeat-character printing rate of the typewriter.

quent necessity to reproduce repetitively occurring alphanumeric characters and symbols has heretofore limited the maximum type reproduction rate of the typewriter to that at which a single type bar can be operated in repetitive type-reproduction manner. Were it not for such type bar repeat-character operational limitation, the reproduction rate of the typewriter could be substantially increased and would then only be limited by the possible overlapping of two adjacent type bars moving simultaneously.

It is an object of the present invention to provide a novel repeat-character-delay code translator system which enables automatic operation of a typewriter at a normal printing rate substantially higher than that heretofore readily available, as conventionally limited by the repetitive operation of a single type bar, and accomplishes this by automatic reduction of the printing rate upon any brief or prolonged repetitive operation of any type bar.

It is a further object of the invention to provide a new and improved typewriter repeat-character-delay code translator system particularly suitable for attaining a significantly higher than normal printing rate in typewriters controlled for automatic high-rate reproduction of alphanumeric characters and symbols read from a record medium or supplied from a similar information source.

It is an additional object of the invention to provide a repeat-character-delay code translator system of relatively simple and inexpensive construction readily incorporated into present-day typewriter structures to enhance their print-reproduction operating rate, and one exhibiting high reliability free of operational error and requiring minimized service attention over prolonged operational intervals.

Other objects and advantages of the invention will appear as the detailed description thereof proceeds in the light of the drawings forming a part of this application and in which:

FIG. 1 is an elevational cross-sectional view illustrating the general type bar operating mechanism of a conventional electric typewriter having a code translator for automatic print reproduction of coded data and functional control information supplied to the typewriter as from a punched tape reader or other like data source, and thus one typical of such structures in which the present invention has high utility;

FIG. 2 is an elevational side view illustrating an end portion of a conventional code translator and particularly shows the clutch controlled cyclic power drive of the translator, and FIG. 3 illustrates in isometric view the general construction of a conventional code translator such as that used in the typewriter construction of FIG. 1;

FIG. 4 is a diagram of an electrical circuit used in a typewriter repeat-character-delay code translator system embodying the present invention in a particular form, FIG. 4a being a fragmentary circuit diagram used in conjunction with certain electrical contact operational relationships and certain circuit voltage relationships graphically represented in FIG. 5 as an aid in explaining the operation of this form of the invention;

FIG. 6 is a diagram of an electrical circuit used in a repeat-character-delay code translator system embodying the present invention in a modified form; and

FIG. 7 shows circuit voltage and electrical contact operational relationships and is used in explaining the operation of the FIG. 6 modification of the invention.

The repeat-character-delay system of the present invention is particularly suitable for incorporation into otherwise conventional electric typewriters operated under the control of code translators for automatic print reproduction of coded information derived from data punched tape, tabulating cards, and like sources of data information. In order more fully to understand how the

The present invention relates to code translator systems and structures and particularly to such systems and structures suitable for automatic print reproduction of data and functional control information supplied to a typewriter as, for example, from a punched paper tape. In greater particularity, the invention concerns a typewriter repeat-character-delay system for enabling operation of the typewriter at a high information print reproduction rate while temporarily reducing the operating rate whenever print reproduction of repetitive characters is required.

The widespread preparation of originally typed documents essentially identical in content may be accomplished rapidly and at low cost by the use of typewriters automatically controlled in operation by data and functional control information supplied from a data source such as a punched tape reader. Typical examples of typewriter-reader structures for this purpose are disclosed in the U.S. Patent No. 2,700,447, granted Jan. 25, 1955 to Edwin O. Blodgett and U.S. Patent No. 2,905,298, granted Sept. 22, 1959 to Edwin O. Blodgett and Wilbur C. Ahrns. The operating print-reproduction speed limitation in such automatically controlled typewriters is established by the operating rate of the typewriter printing mechanism, and particularly by the maximum rate at which any given type bar may be moved from a position of rest to a type impression position and returned to its position of rest. The fre-

present invention is so incorporated into such typewriters, and to perceive the novel and important operational results attained thereby, consideration will first be briefly directed to the construction and operation of the general type bar operating mechanism of a typical electric typewriter and its associated code translator control which enables automatic print reproduction of data read from a punched tape or tabulating card by a conventional tape or card reader as in the aforementioned Blodgett patents.

Referring now more particularly to FIG. 1 of the drawings, certain features of conventional typewriter construction and operation of particular interest in relation to the present invention are illustrated in elevational cross-sectional view. Reference may be made to the aforementioned patents for an understanding of the more complete construction and operation of such typewriters and of a punched tape data reader forming a component unit thereof for use in automatic print reproduction of data and functional control information read from the punched tape. The typewriter includes a conventional curvilinear anvil member 10 carrying a support wire or small rod 11 upon which the usual type bars 12 are pivotally supported for reciprocal angular motion between a position of rest against a stationary rest bar 13 and a type impression position at which type characters 14 fixed to the type bar 12 impact through a print ribbon (not shown) paper wrapped around the typewriter platen (not shown). As illustrated for one type bar 12 but duplicated for other such type bars, an articulated toggle member 15 is pivotally supported at one end on a fixed shaft 16 and is pivotally supported at its opposite ends on a pin 17 secured to an extended end of the type bar 12. A helical wire spring 18 normally maintains the type bar 12 in its position of rest at which the toggle 15 is straightened. Angular power drive of the type bar 12 to print position is effected by a link member 19 which mechanically connects a bell-crank arm 20 of the toggle 15 to an arm 21 of a bell crank 22 pivotally supported upon a fixed shaft 23. A second arm 24 of the bell crank 22 has an extended portion 25 which, in the rest position of the type bar 12, engages a stop bar 26 supported upon a frame 27 secured between the side frames of the typewriter structure. The arm 24 of the bell crank 22 is mechanically connected through a link member 30 to an actuating bell crank 31 pivotally supported upon a shaft 32 and pivotally supporting a cam actuator 33. Alternate type bars 12 in the type basket are mechanically connected by the structure just described to individual ones of a row of bell cranks 31 positioned forwardly (with respect the forward end of the typewriter) of a power roll 34 rotationally supported on a shaft 35 between the side frames of the typewriter and power driven at constant velocity by a drive motor, not shown. The intervening type levers of the type basket are mechanically connected by a similar structure to that just described and which includes a bell crank 22' mechanically connected by a link member 30' to an individual one of a rearwardly positioned row of bell cranks 31' pivotally supporting individual cam actuators 33' and pivotally supported upon a shaft 32'.

The typewriter bell cranks 31 and 31' are provided with latch structures, not shown, by which the bell cranks are latched in a position such that their associated cam actuators 33 and 33' are out of engagement with the power roll 34. Upon manual actuation of a typewriter key button 36 angularly to depress an associated key lever 37 pivotally supported on the shaft 23 and normally biased by an individual helical wire spring 38 to non-depressed position, an extension arm 39 or 39' of the key lever 37 unlatches an associated bell crank 31 or 31' which thereupon pivots under force of a bias spring (not shown) to engage the associated cam actuator 33 or 33' with the power roll 34. The cam actuator 33 or 33' is thereupon rotated by the power roll 34 to pivot the associated bell crank 75

31 or 31' away from the power roll so that the remote end of the bell crank pulls down upon the associated link member 30 or 30' angularly to move (in a counterclockwise direction as seen in FIG. 1) the associated bell crank 5 22 or 22'. This angular motion of the latter bell crank operates through the link member 20 and toggle 15 to move the associated type bar 12 from its position of rest to its type impression position, the type bar thereafter returning to rest position under the bias force exerted by its associated spring 18. To permit any type bar 12 to 10 accomplish successive cycles of movement to type impression position and return to its rest position as required in typing successive repetitions of the same alpha-numeric character or symbol by the type bar, it has been conventional heretofore to limit the maximum rate of type reproduction to that required for a type bar 12 to complete each cycle of movement from its position of rest to its type impression position and return to its position of rest. Such reproduction rate thus is limited not only by the 15 inertial mass of the type bar but by that of all mechanical components which are connected to and move with the type bar. This limitation on the operating rate is conventionally established in any of several well known manners, such as by design selection of the maximum diameter of the cam actuators 33 in relation to the diameter 20 of the power roll 34 and by selection of the rotational velocity of the latter.

The typewriter operation just described in relation to 25 manual operation of a key button 36 may also be accomplished automatically under control of a conventional code translator 40. The latter was the general construction and operation more fully disclosed and described in a copending application of Donald G. Bastian, Ser. No. 582,134 (now U.S. Patent No. 3,340,987) filed concurrently herewith and assigned to the same assignee as the present application, and will only briefly be described hereinafter as necessary to an understanding of the present invention. It is controlled by permutational energizations of electrical code circuits corresponding to each 30 data and functional control code supplied by a data source such as a punched tape reader. To this end, the translator 35 40 includes a plurality of seekers 41 each having a hooked end 42 engaging a pin 43 secured to the side of an individual one of the key levers 37 so that longitudinal power-drive movement of a seeker 41 by the code translator 40 45 pulls down an associated key lever 37 to cause operation of a type bar 12 in the same manner as just described for manual operation of a key button 36.

As illustrated in FIGS. 1 and 2, the code translator 40 50 is power driven by a pulley 46 and belt 47 from the typewriter motor (not shown) and includes a translator cycle control clutch 48 of the helical wire spring type having a construction and mode of operation more fully disclosed and described in connection with FIGS. 5, 6 and 7 of the U.S. Patent No. 2,927,158, granted Mar. 1, 1960, 55 to Edwin O. Blodgett. The clutch 48 is provided with an electromagnet 49 which is briefly energized to initiate a cycle of translator operation. Such energization is accomplished at a time and in a manner presently to be explained, and effects attraction of a pivoted armature 60 50 against the bias force of a spring 51 to withdraw the end of the armature structure from engagement with a stop detent protuberance 52 provided on the peripheral surface of the clutch housing 53. This permits initiation 65 of a cycle of clutch operation to drive a translator shaft 54 from the drive pulley 46. In a first embodiment of the invention hereinafter described, the clutch includes only one stop detent protuberance 52 so that the clutch operating cycle effects a 360° rotation of the translator shaft 54 and thus drives the translator through a complete cycle 70 of translator operation each time the electromagnet 49 is energized. A second described embodiment of the invention utilizes a translator clutch having an additional stop detent protuberance positioned to halt the clutch at 140° 75 of its operating cycle just prior to power drive downward

movement of one of the translator seekers 41. This partial-revolution form of clutch accordingly requires brief energization of the electromagnet 49 to initiate a cycle of clutch drive operation by releasing the clutch past its 0° or home position and requires a second brief energization of the electromagnet 49 to permit completion of the cycle of clutch operation by releasing the clutch past its 140° halt position. In either of these forms of clutch, however, the electromagnet 49 is deenergized prior to the end of the clutch drive cycle to permit the spring 51 to move the end of the armature structure 50 to a position where it again engages the protuberance 52 and thereby terminates the clutch drive cycle. An armature knock-off cam 55 and cam follower bell crank 56 biased into relative engaging relationship by a spring 57 forcibly moves the armature structure 50 away from the electromagnet 49 just prior to the end of the clutch cycle to prevent retention of the armature structure in attracted position by reason of any prevailing residual magnetic field. A pivoted detent member 58, biased by a spring 59 to engage a detent notch provided in the peripheral surface of a collar 60 secured to the driven shaft 54, prevents reverse rotation of the latter upon completion of the clutch drive cycle.

As illustrated in FIGS 2 and 3, the translator 40 includes a plurality of code permutation slides 65 supported by slotted end guide members (not shown) for longitudinal reciprocal motion between a reset position and a code selective unlatched position. Just prior to completion of each translator operating cycle, a cam 66 on the shaft 54 pivotally moves a cam follower lever 67 angularly to pivot a reset bell crank 68 about a shaft 69 normal to the direction of motion of the permutation slides 65. This reset angular motion of the reset bell crank 68 engages the end of the latter with a notch 70 provided in an edge of the permutation slides 65 to move all of these slides concurrently to a reset position. Each of the permutation slides 65 is provided with an edge latch protuberance 71 arranged in groups as shown, and the slides are retained in latched position by engagement of their latch protuberances 71 with latch notches provided in the end surface of the pivoted armature 72 of a code selective electromagnet 73 individual to each permutation slide 65. Having thus been moved to latched position by the latch bell crank 68, the latter is angularly moved out of engagement with the slide notches 70 to permit each permutation slide to move under the bias force of an individual helical wire spring 74 to an unlatched position upon energization of its associated electromagnet 73 to attract its armature 72 out of latching engagement with the latch protuberance 71 of any such slide to be so unlatched. Each coded data and function control information item is supplied in the form of permutational code energizations of electrical circuits individual to the electromagnets 73 as will presently be described more fully, so that each such supplied coded information item causes permutational energization of selected ones of the electromagnets 73 to release selected ones of the permutation slides 65 to unlatched position while the remaining unenergized ones of the electromagnets 73 retain their corresponding permutation slides 65 in latched position.

The permutation slides 65 are identically notched along one edge to provide a plurality of equally spaced code selective projections 78 and these projections of the slides 65 are all aligned with one another in the reset position of the latter. The projections 78 of any unlatched permutation slide 65 move to a central position between the projections 78 of latched permutation slides. A cam 79 thereafter pivotally moves a seeker bail 80 supported by arms 81 on a shaft 82 to permit all of the seekers 41, pivotally supported on the shaft 82, angularly to move under bias force of an individual tension spring 83 toward the projections 78 of the permutation slides. The seekers 41 are provided along their length with tines 84 individual

to each of the permutation slides 65 and laterally displaced in alignment with a projection 78 or the space between two such projections when the individual slide is in either latched or unlatched position. By selecting the pattern of laterally displaced tines 84 on each seeker 41, the tines provided on only one of the seekers 41 will fail to engage any projection 78 of any of the permutation-code-positioned permutation slides 65 for each possible such permutational positioning. This one selected seeker will thus pivotally move to an actuation position at which a seeker notch 85 is engaged by a seeker actuating bail 86. All others of the seekers 41 will be restricted in their angular motion by reason of the fact that at least one of their tines 84 will engage at least one projection 78 on the permutation-code-positioned permutation slides 65. The seekers 41 are fabricated of two elongated members of which one is pivotally supported upon the shaft 82 and the other carries the notch 85 together with the hooked end portion 42 and is reciprocally movable longitudinally of the pivotally supported member. After one of the seekers 41 has been selected by the permutational setting of the slides 65 in the manner just explained, a cam 87 on the shaft 54 actuates a cam follower bell crank 88 pivoted on a stud shaft 89 angularly to reciprocate the seeker actuating bail 86 through a cycle of angular motion. This motion of the actuating bail 86 engages the notch 85 of the selected seeker 41 to effect a downward movement of the hooked end portion 42 of the selected seeker and thus actuate an individual key lever of the typewriter structure as earlier explained. The bail 80 then withdraws all of the seekers 41 from engagement with the slides 65, and the latter are thereafter reset to latched position to await a further cycle of translator operation.

A cam 90 on the shaft 54 operates electrical contacts STC1 to closed-contact position between approximately 180° of one translator cycle and 20° of the following cycle for an electrical control function presently to be described.

FIG. 4 shows the electrical circuit diagram employed in a repeat-character-delay system embodying the present invention in a particular form. The source of coded data and functional control information is here shown by way of example as one of the punched tape reader type as in the above-mentioned Blodgett and Blodgett et al. patents. Such a reader operates in successive reader cycles each initiated by energization supplied to a reader clutch magnet LRC through a manually closed switch S and the cam-actuated contacts STC1 of the above-described code translator 40 when these contacts close between 180° of one translator cycle and 20° of the next cycle. The reader is provided with electrical contact sets, shown for example as comprised by six such sets RC1-RC6, which under control of the reader code-aperture sensing pins are individually selectively operated to closed-contact position each time an associated sensing pin senses a corresponding aperture in the punched code read during the reader cycle. As the reader cycle progresses the contacts 1 and 2 of the reader contact sets RC1-RC6 are closed at time t_0 and open at time t_3 after, the interval t_1-t_2 of closure of the contacts 1 and 2 of a set of reader cam-actuated common contacts RCC as graphically represented by respective curves A and B of FIG. 5. Upon closure of the contacts 1 and 2 of the reader common contacts RCC, energization is supplied through the contacts 1 and 2 of any operative ones of the reader contact sets RC1-RC6 to the corresponding code selector electromagnets 73 of the code translator 40 to unlatch corresponding ones of the permutation slides of the latter. The code translator 40 may have its clutch magnet LTC concurrently energized to initiate a cycle of translator operations unless such energization is delayed for a preselected interval, thus to delay the translator cycle and corresponding delay a typewriter key lever operation, by the sensing of a repeat character for print reproduction. The

manner and effect of such repeat character sensing will now be considered.

Each coded alpha-numeric, symbol and functional control item of information recorded in the punched tape is identified by an individual distinctive punched-aperture code comprised by the permutational combination of punched apertures and the lack thereof at preselected transverse positions (often identified as code "channels") aligned transversely of the tape and sensed by an aligned row of reader sensing pins. It is convenient to refer to a punched code aperture in the tape as one code bit causing closure of the contacts 1 and 2 of a corresponding one of the reader contact sets RC1-RC6 and to refer to the absence of an aperture as a zero code bit which prevents closure of the contacts 1 and 2 of a corresponding reader contact set RC1-RC6. The repeat-character-delay system includes a multi-bit information-item storage register for individually storing the zero and one code bits identifying each coded information item successively read from the punched tape. This storage register is conveniently comprised of a plurality of bistable multivibrators 95-1-95-6 each utilizing a pair of transistors Q₁ and Q₂ arranged in a conventional electrical circuit as shown for the multivibrator 95-1. Each of the reader contact sets RC1-RC6 includes transfer contacts 3-5 of which the fixed contacts 4 and 5 are connected to the collector electrodes of the respective transistors Q₁ and Q₂. These fixed contacts control the individual conductive states of these transistors according to the transferred or non-transferred state of the movable contact 3 at the time t₁ when the contacts 3 and 4 of the reader common contacts RCC close to apply ground potential through a diode 96 to a conductor 97 which is connected through a plurality of diodes 98-1-98-6 to the contact 3 of the respective reader contact sets RC1-RC6. Thus with respect the multivibrator 95-1, the transistor Q₂ will be rendered conductive to store a zero code bit if the contacts 3 and 5 of the reader contact set RC1 are closed at the t₁ when the contacts 3 and 4 of the reader common contacts RCC close, or alternatively the transistor Q₁ will be rendered conductive to store a one code bit if the contacts 3 and 4 of the reader contact set RC1 are closed when the contacts 3 and 4 of the reader common contacts RCC close. When the transistor Q₂ is conductive to store a zero code bit, the non-conductive state of the transistor Q₁ applies a negative potential to the contact 4 of the reader contact set RC1 to indicate the storage of the zero code bit; conversely, the storage of one code bit by the conductive state of the transistor Q₁ causes the non-conductive transistor Q₂ to apply negative potential to the contact 5 of the reader contact set RC1 to indicate such storage of the one code bit. Upon opening of the contacts 3 and 4 of the reader common contacts RCC at the time t₂, of the multivibrators 95-1-95-6 are thus left set storing individual one and zero code bits to the previously operated states of their associated reader contact sets RC1-RC6. The set state of each multivibrator by energizing its associated contacts 4 and 5 indicates whether the multivibrator stores a one or zero code bit.

The conductor 97 is connected to ground through a resistor 101 and is coupled through a series resistor 102 and a series condenser 103 to the base electrode 104 of a transistor Q₃. The latter has its emitter electrode connected to ground potential, has a series collector load resistor 105, and is normally conductive by reason of a negative bias potential applied to the base electrode 104 through series resistors 106 and 107 from a source of negative potential as shown. In the interval between each successive operation of the reader contact sets RC1-RC6, the contacts 3-5 of the reader contact sets RC1-RC6 will usually maintain the conductor 97 at a negative potential for reasons presently to be explained, and the condenser 103 accordingly charges to a negative potential with respect to ground through the resistors 101, 102, 106 and 107. Assuming that a new code causing operation of the

reader contact sets RC1-RC6 corresponds to a previous code stored by the multivibrators 95-1-95-6, as represented for example by the transferred states of the reader contact sets RC3 and RC6 and the non-transferred states of RC4 and RC5 of the fragmentary circuit diagram of FIG. 4a, zero or ground potential is then supplied by the multivibrators to the transferred and non-transferred contacts 3 of all the reader contact sets RC1-RC6 and this causes the conductor 97 also to be at zero or ground potential. The condenser 103 thereupon discharges during the time interval t₀-t₁ at a relatively slow rate through the resistors 102, 105 and 106 and reaches ground potential by the time contacts 3 and 4 of the reader common contacts RCC close at time t₁. The closure of these contacts then does not affect the charge of the condenser 103 during the interval t₁-t₂ of closure of the reader common contacts RCC as represented by curve C of FIG. 5. When the operated ones of the reader contact sets RC1-RC6 return at time t₃ to their non-operated states as represented in broken lines for the contact sets RC3 and RC6 in FIG. 4a, the contacts of these contact sets will be negatively energized by the storage state of their associated multivibrators 95-1-95-6 and thus will place negative energization upon the conductor 97. The condenser 103 thereupon recharges through the emitter-base electrodes of the transistor Q₃ once more to a negative potential with respect to ground as further represented by curve C of FIG. 5. The discharge and charge voltage thus applied by the condenser 103 to the base electrode 104 of the transistor Q₃ under the condition here assumed is graphically represented by curve D of FIG. 5 and does not affect the continuing state of conductivity of the transistor Q₃. The condition assumed, however, is one involving a repeat character wherein successive identical codes are read by the reader contact sets RC1-RC6 which upon being operated by the second of such codes effectively coincidence sample the previously stored code and find successive code identity. The energization of the translator clutch magnet 49 is accordingly delayed in a manner which will now be considered.

The present system includes a delay means comprised by a monostable multivibrator 110 having a pair of transistors Q₄ and Q₅ arranged in a conventional monostable multivibrator circuit in which the transistor Q₄ is normally conductive and transistor Q₅ normally nonconductive. In the intervals between the closure of the contacts 3 and 4 of the reader common contacts RCC, a condenser 111 is charged to the polarity shown in the drawing by charging current supplied from a negative energizing source through series resistors 112 and 113. When the contacts 3 and 4 of the reader common contacts RCC close at time t₁ as represented by curve B of FIG. 5, the condenser 111 is rapidly discharged through the resistor 113 to produce across the latter a positive voltage pulse. This voltage pulse is supplied through a diode rectifier 114 to the base electrode of the transistor Q₄ to render the latter non-conductive and thereby render the transistor Q₅ conductive, whereupon a negative potential pulse is applied through a series resistor 115 and a series condenser 116 to the base electrode 104 of the transistor Q₃. This negative potential pulse does not affect the continuing state of conductivity of the transistor Q₃. After a preselected time interval established in well-known manner by selection of the component values of the multivibrator 110, the transistor Q₅ becomes non-conductive to render the transistor Q₄ again conductive and thereby to supply through the resistor 115 and condenser 116 a positive potential pulse to the base electrode 104 of the transistor Q₃.

This positive potential pulse renders the transistor Q₃ non-conductive. The transistor Q₃ upon thus becoming non-conductive renders a transistor Q₆ conductive to energize a relay winding 117 from a conventional negative energy source shown as of the half-wave rectification type including a transformer 118 having a primary winding 119 energized from a suitable alternating source and

having a secondary winding 120 which is connected through a diode rectifier 121 to an output filter network comprising a shunt filter condenser 122 and shunt resistor 123. Energization of the relay winding 117 effects closure of its contacts 1 and 2 to energize the translator clutch magnet 49 and thus initiate a cycle of translator operation in the manner previously explained. The transistor Q_6 is included with the transistor Q_3 in a monostable multivibrator circuit which includes a diode rectifier 126 in the emitter electrode circuit of the transistor Q_6 , a diode rectifier 127 coupling the collector electrode of the transistor Q_6 through a resistor 128 to the negative energizing source of the transistor Q_3 , and a condenser 129 which couples the emitter electrode of the transistor Q_6 through the diode rectifier 127 to the juncture of the bias resistors 106 and 107 of the transistor Q_3 . The component values of this multivibrator circuit are so selected in well-known manner that the transistor Q_6 remains conductive during a brief interval while the charge of the condenser 129 changes to maintain the transistor Q_3 non-conductive after which the latter becomes conductive once more and renders the transistor Q_6 non-conductive. This deenergizes the relay winding 117 which opens its contacts 1 and 2 to deenergize the translator clutch magnet 49, so that the conductive interval of the transistor Q_6 releases the translator clutch past its home or zero-cycle position but deenergizes the translator clutch magnet 49 sufficiently early in the translator cycle that the translator may again be halted at its home position by the deenergized state of the translator clutch magnet 49.

Thus upon the reading of successive identical codes by the reader contact sets RC1-RC6 as indicative of a repeat character operation, the multivibrator 110 so controls the transistor Q_3 as to delay for a pre-selected interval (established by the multivibrator 110) the energization of the translator clutch magnet 49 and thereby the initiation of the succeeding cycle of operation of the translator. The translator cam-actuated contacts STC1 cause this delayed operation of the translator in turn to delay the initiation of a succeeding cycle of operation of the punched tape reader, and the translator delay permits the selected typewriter type bar to complete an initial full cycle of its reciprocatory motion in effecting print reproduction of the repeated character.

When the reader contact sets RC1-RC6 read successive codes representing differently coded alpha-numeric and symbol characters, it will be evident that upon reading the second of such successive codes the transfer contacts 3 of the contact sets will find at least one of the contacts 4 and 5 associated with at least one of the multivibrators 95-1-95-6 negatively energized by reason of the differing codes read. For example, assume that the first of two successive codes operates the reader contact sets RC3 and RC6 as shown in FIG. 4a and that the second of the codes operates either of the contact sets RC4 or RC5 or fails to operate both of the contact sets RC3 and RC6. Under this assumed condition, at least one of the contacts 3 of these contact sets will move into engagement with an associated negatively energized contact 4 or will remain in contact with a negatively energized conductor 4. The reading of two successive differing codes thus places the conductor 97 at a negative potential with respect to ground during the initial portion t_0-t_1 of the contact set operating interval t_0-t_3 so that the charge of the condenser 103 does not change in the time interval t_0-t_1 as represented by curve E of FIG. 5. Now when the contacts 3 and 4 of the reader common contacts RCC close at time t_1 , the condenser 103 is rapidly discharged at time t_1 through the reader common contacts RCC as further shown by curve E. This effectively places a positive potential pulse at time t_1 on the base electrode 104 of the transistor Q_3 , as graphically represented by curve F of FIG. 5, to render the transistor Q_3 non-conductive. The transistor Q_6 is thereupon rendered conductive to effect immediate energization of the translator clutch magnet 49 at time t_1 without delay

The multivibrator 110 has its cycle of operation also initiated at time t_1 , in the manner earlier described, by closure of the contacts 3 and 4 of the reader common contacts RCC. However, the negative pulse applied at this time by the multivibrator 110 to the base electrode 104 of the transistor Q_3 is selected to be appreciably smaller in amplitude than the positive potential pulse applied by the condenser 103 to the transistor Q_3 so that the latter pulse is effective at time t_1 to render the transistor Q_3 non-conductive as just described. The transistor Q_3 remains non-conductive during the operating cycle of the multivibrator 110, and the positive potential pulse later applied to the transistor Q_3 upon completion of the multivibrator 110 operating cycle accordingly has no effect on the conductive state of the transistor Q_3 .

Thus it will be seen that whereas the reading of successive identical codes by the reader contact sets RC1-RC6 effects delayed energization of the translator clutch magnet 49 in the manner first described, the reading of successive differing codes by the reader contact sets RC1-RC6 effects immediate energization at time t_1 of the translator clutch magnet 49 without delay as last described. This non-delayed energization of the translator clutch magnet 49 to initiate a new non-delayed translator cycle of operation, and thereby a non-delayed reader cycle of operation, enables the typewriter to operate at a higher print reproduction rate by reason of the initiation of a reciprocatory cycle of type bar operation prior to completion of the reciprocatory cycle of operation of the preceding type bar operated.

A special repeat character mode of operation meriting attention concerns the reading of successive blank codes (all zero code bits) and the reading of successive blank and non-blank codes by the reader contact sets RC1-RC6. Assume that a first blank code (none of the reader contact sets RC1-RC6 is operated) is followed by the reading of a second blank code. After the reading of the first blank code, all of the multivibrators 95-1-95-6 have been set to store a zero code bit so that the conductor 97 remains at ground potential after this code is read and to the time t_0 of reading the second blank code. Between the first and second code reading intervals, the charge of the condenser 103 remains essentially at ground potential. Since none of the reader contact sets RC1-RC6 is operated upon reading the second blank code, the charge of the condenser 103 is not affected during the time interval t_0-t_1 of the new code nor is it affected when the contacts 3 and 4 of the reader common contacts RCC close at time t_1 . Thus the transistor Q_3 remains conductive at time t_1 of the second blank code and the energization of the translator clutch magnet 49 is delayed for a preselected interval under control of the multivibrator 110 as earlier described. Assume now that the next or third code read is not a blank code. In this event, at least one of the reader contact sets RC1-RC6 is operated so that the contacts 3 and 4 of such operated contact set or sets now energizes the conductor 97 to a negative potential during the interval t_0-t_1 of this code. The condenser 103 thereupon charges to a negative potential as graphically represented by curve G of FIG. 5, thus applying a negative pulse to the base 104 of the transistor Q_3 to maintain the latter conductive during the interval t_0-t_1 as graphically represented by curve H of FIG. 5. Now when the contacts 3 and 4 of the reader common contacts RCC close at time t_1 , the condenser 103 is rapidly discharged to apply a positive potential pulse to the base 104 of the transistor Q_3 as shown by curve H. This positive pulse renders the transistor Q_3 non-conductive to effect energization of the translator clutch magnet 49 at time t_1 and without delay in the manner explained. Thus the reading of successive blank codes effects delayed energization of the translator clutch magnet 49 with resultant delay in the initiation of a cycle of translator operation, whereas the reading of a blank code followed by a succeeding nonblank code effects non-delayed energization of the translator clutch magnet 49

and thus the initiation without delay of a cycle of the translator operation.

A repeat character delay system embodying the present invention in a modified form utilizes an electrical control system shown in FIG. 6. The code translator in this form of the invention has a partial revolution type of clutch such as that illustrated and described in relation to FIG. 4 of the aforementioned Blodgett et al. Patent No. 2,927,158 except that whereas the Blodgett et al. clutch has 180° physically displaced stop protuberances for halting the clutch at its 0° and 180° cyclic positions the translator clutch of the modified form of the present invention includes stop protuberances at its 0° and 140° cyclic positions.

As shown in FIG. 6, the modified form of the present invention includes a multi-bit information-item storage register of the magnetic core storage type for storing zero and one code bits identifying each coded information item successfully presented for print reproduction. In particular, the register is comprised by a plurality of cores 132-1—132-6 formed of a magnetic material exhibiting a small-area or so-called "square" hysteresis loop and thus one which may be readily saturated in either of two magnetic polarities and which essentially retains its full saturation magnetism upon removal of the magnetizing current. To this end, each core includes a first magnetizing winding 133 which sets the core to one polarity of magnetic saturation representing storage of a one code bit, includes a second magnetizing winding 134 which "resets" the core to the opposite polarity of magnetic saturation representing storage of a zero code bit, and includes an output winding 135 in which an output potential pulse is developed if there is a change in the setting of the core from one to the other of its polarities of magnetic saturation.

The contacts 1 and 2 of the reader contact sets RC1-RC6 close upon reading individual one code bits of an information-item code as previously described, and upon closing energize an associated translator code magnet 73 in series with the first energizing winding 133 of the associated magnetic storage core 132-1—132-6. If any such core was previously set to a magnetic polarity of saturation corresponding to the storage of a zero code bit, energization of the first energizing winding 133 reverses the polarity of magnetic saturation of the core and thus produces an output potential pulse in the output winding 135 of this core. All of the output windings 135 of the several storage cores are connected in series to a diode bridge rectifier 136 so that an output pulse produced in the manner last described is supplied through the rectifier 136 to the gate electrode 137 of a silicon controlled rectifier 138. The interval of closure t_0-t_3 of the contacts 1 and 2 of the reader contact sets RC1-RC6 is graphically represented by curve J of FIG. 7, and the output pulse thus applied to the gate electrode 137 of the silicon controlled rectifier 138 occurs at time t'_1 when the reader contacts RCC first operate as graphically represented by curve K of FIG. 7. This applied pulse renders the silicon controlled rectifier 138 conductive by energization supplied through the normally closed contacts of translator cam actuated contacts STC2 and a current limiting resistor 139 having connected in shunt thereto a series circuit comprising a diode rectifier 140 and the relay energizing winding 117. The relay is concurrently energized directly at time t'_1 by closure of the contacts 1 and 2 of the reader common contacts RCC, and upon being thus energized closes its contacts 1 and 2 to energize the translator clutch magnet 49 and initiate a cycle of translator operation by releasing the clutch from its 0° or home position. The conductive state of the silicon controlled rectifier 138 continues until later terminated in a manner presently to be explained, and thus maintains the relay winding 117 energized sufficiently long as to release the clutch past its 140° halt position by continued energization of the clutching

magnet 49. The translator thus completes its cycle of operation without delay.

It may be noted that the storage core output pulse produced as last described signifies a change in at least one code bit of the code presently read by the reader contact sets RC1-RC6 and the code previously read and stored in the magnetic storage cores 132-1—132-6, so that the silicon controlled rectifier 138 in being immediately rendered conductive effects by its continuing state of conductivity immediate energization of the translator clutch magnet 49 past the 140° halt position of the translator clutch to complete a translator cycle of operation without delay.

If upon reading the new code the operated reader contacts RC1-RC6 in energizing the corresponding energizing windings 133 of their associated cores do not cause any core to produce an output pulse in its output winding 135, this signifies that all of these cores store a one code bit of the preceding code and to this extent indicates that the present and previous codes are the same. The contacts 1 and 2 of the reader common contacts RCC close at a time t'_1 and open at a time t'_2 as graphically represented by curve K of FIG. 7, and upon closing energize the relay winding 117 to initiate a translator cycle of operation as earlier described. The translator cycle thus begins even though the silicon controlled rectifier 138 does not become conductive at this time. As the translator progresses through its cycle of operation, a pair of translator cam actuated contacts STC3 close at time t_4 as graphically represented by curve L of FIG. 7. The closure of these contacts supplies energization to the reset winding 134 of all of the storage cores 132-1—132-6 to change the polarity of magnetic saturation of those cores which previously stored a one code bit and which are not presently retained in their one polarity of magnetic saturation by the continuing closure of the contacts 1 and 2 of the associated reader contact sets RC1-RC6. Should this energization of the reset windings 134 produce an output pulse in the output winding 135 of any core, the output pulse as before is supplied through the bridge rectifier 136 to the gate electrode 137 of the silicon controlled rectifier 138 to render the latter conductive. The relay winding 117 and translator clutch magnet 49 are thereupon energized to release the translator clutch without significant delay past its 140° halt position in the manner previously described. It may be noted here again that any such output pulse developed as last described signifies that the presently read code differs in respect at least one zero code bit from the code previously read and stored in the magnetic storage cores, so that the translator cycle of operation may accordingly be completed without delay.

It will be evident in light of the operations just described that energization of the first energizing winding 133 under control of the operated reader contact sets RC1-RC6 samples any differences existing between the one bits of the code presently read and the corresponding one bits of the previous code stored by the storage cores, that the energization of the reset windings 134 under control of the cam actuated contacts STC3 samples the differences between the zero code bits of the present code and corresponding zero bits of the previous code stored by the storage cores, and that any difference of a zero or one bit between the present and previous codes signifies that the present code is different from the previous code and thus that the translator clutch magnet 49 may be promptly energized to release the translator clutch past its 140° halt position and complete the translator cycle without delay.

Should the silicon controlled rectifier 138 not be rendered conductive at or prior to the time the reset windings 134 are energized by the translator cam actuated contacts STC3, it will be evident from what has just been said that there is identity of all code bits as between the present code and that previously read and stored in the storage cores. This code identity requires delay in com-

pleting the cycle of translator operation, and this is accomplished by delaying the second energization of the translator clutch magnet 49 to halt the translator for a brief interval at its 140° cyclic position. Such delay is provided by translator cam actuated contacts STC4 which close at time t_4 just prior to and during the halt of the translator at its 140° cyclic position as graphically represented by curve M of FIG. 7. These contacts upon closing charge a condenser 142 through a resistor 143 until the charge potential of the condenser 142 increase to a value sufficient to produce breakdown of a Zener diode 144, at which time the charge potential of the condenser 142 is applied to the gate electrode 137 of the silicon controlled rectifier 138 to render the latter conductive. The conductive state of the silicon controlled rectifier 138 now energizes the translator clutch magnet 49 in the manner previously described to release the translator past the 140° cyclic position at which it was halted.

Once the silicon controlled rectifier 138 has been rendered conductive to energize the translator clutch magnet 49 with or without delay, it remains energized until it is deenergized by the opening of the translator cam actuated contacts STC2 at time t_5 as graphically represented by curve N of FIG. 7. The time t_5 of opening of the latter contacts occurs toward the end of the translator cycle of operation, but is yet sufficiently early in the cycle as to permit the translator to halt at its 0° or home position.

It will be evident from the foregoing description of the invention that the invention provides a new and improved typewriter repeat-character-delay code translator system particularly suitable for attaining a significantly higher than normal printing rate in type-writers controlled for automatic high-rate reproduction of alphanumeric character and symbols read from a record medium or supplied from a similar information source. The invention has the further advantage that it not only enables automatic operation of typewriters at a normal printing rate substantially higher than that heretofore readily available, as conventionally limited by the repetitive operation of a single type bar, but additionally is of relatively simple and inexpensive construction readily incorporated into present-day typewriter structures and exhibits high reliability free of operational error and requiring minimized service attention over prolonged operational intervals.

While there have been specific forms of the invention described for purposes of illustration, it is contemplated that possible changes may be made without departing from the spirit of the invention.

What is claimed is:

1. A repeat-character-delay code translator system comprising:

(a) cyclic code translator means adapted for automatic print control of a typewriter having a plurality of key levers, and

(b) a mechanical power drive translator cycle-control clutch which initiates each new translator cycle during which

(1) translator permutation slides are set to permanent positions according to individual ones of the code elements in each of successive multiple-code-element permutation electrical codes supplied to said translator and in which

(2) a plurality of translator seekers test the permutational setting of said slides for individually selecting one of said seekers for power drive actuation of one of said typewriter key levers to print successive alpha-numeric and symbol characters during each of successive translator cycles and at a second cyclic rate higher than a first rate,

(c) electrical storage means for storing during an interval following completion of each translator cycle

the permutation code presented during said each translator cycle, and

(d) repeat-character means for coincidence sampling of the code stored by said storage means with a code newly presented to ascertain the identity, or the lack of identity, between the permutation code supplied to said translator in respect each preceding and new translator cycle, and

(1) operative upon each ascertainment of permutation-code identity for controlling said translator cycle-control clutch to delay for a pre-selected interval the said new translator cycle, and

(2) thereby delay the reinterpretation and utilization of the said newly presented permutation code by said translator temporarily to reduce the cycle operating rate of said translator from said second rate to said first rate,

(3) said first rate being determined by said repeat character means and independent of the cycle operating rate of said translator cycle-control clutch, thereby enabling said second rate to be other than an integer multiple of said first rate.

2. A typewriter repeat character delay system according to claim 1, and including:

(a) cyclic source means for selectively halting said translator at an intermediate position of a cycle of operation of said translator and at a home position marking completion of each cycle of said translator operation, and wherein

(b) said repeat-character means controls said cyclic source means to release said translator past said home position thereof upon each new presentation of a permutation code, and

(1) to release said translator without delay past said intermediate position thereof in the absence of said permutation code identity, and

(2) with preselected delay upon each occurrence of said permutation code identity.

3. A typewriter repeat character delay system according to claim 1 wherein said repeat-character means includes:

(a) time-delay means, and
(b) controls said cycle-control clutch independent of said time-delay means to initiate a new translator cycle without delay in the absence of said permutation code identity, but wherein

(c) said time-delay means controls said cycle-control clutch to initiate a new translator cycle after said preselected interval upon each occurrence of said permutation code identity.

4. A typewriter repeat-character-delay system comprising:

(a) a plurality of individually operable alpha-numeric and symbol type-body supporting members each having a first operating rate to effect type print impressions,

(b) cyclic source means including source-cycle control means for presenting successive electrical coded signals representing coded alpha-numeric and symbol information items successively presented for printing at a second rate higher than said first operating rate;

(c) cyclic printing means including:

(1) print-cycle control means, and

(2) print control means controlled by said electrical signals for operating said type supporting members to print said information items in succession at said second rate;

(d) means responsive to substantial completion of each operating cycle of said printing means for controlling said source-cycle control means to initiate a further cycle of operation of said source means,

(e) storage means electrically controlled by said source means for storing during an interval following each

- print cycle an identification of the coded signals presented during said each print cycle,
- (f) means including an electrical condenser responsive to the prevailing coded-signal identification stored by said storage means for respectively producing said suppressing production of an electrical energy pulse upon each condition of identity and lack of identity between the coded signals presented in respect each preceding and new print cycle, and
- (g) repeat-character delay means responsive to each said production and suppression of production of said electrical energy pulse for controlling said print-cycle control means respectively to
- (1) utilize the newly presented coded signals without delay and
  - (2) temporarily to delay the utilization thereof by said print control means and thereby permit said printing means to print at said second printing rate in the absence of said coded-signal identity while temporarily reducing said cyclic printing rate to said first rate upon each occurrence of said coded-signal identity,
  - (3) said first rate being determined by said repeat character means and independent of the cycle operating rate of said translator cycle-control clutch, theretby enabling said second rate to be other than an integer multiple of said first rate.
5. A typewriter repeat-character-delay code translator system comprising:
- (a) a plurality of individually operatable alpha-numeric and symbol type-body supporting members each having a first operating rate to effect type print impressions in response to the actuation of an associated typewriter key,
  - (b) cyclic source means including:
    - (1) a source-cycle control means for controlling the presentation of successive electrical coded signals, representing coded alpha-numeric and symbol information items to be successively presented for printing, at a second rate higher than said first rate,
  - (c) cyclic printing means including:
    - (1) a code translator having a mechanical power drive cycle-control clutch which is controlled by said cyclic source means and initiates each new translator cycle during which
    - (2) translator permutation slides are set to permutational positions under control of code electromagnets controlled by said electrical coded signals, and in which
    - (3) a plurality of translator seekers test the permutational setting of said slides for individually selecting one of said seekers for power drive actuation of one of said typewriter key levers to operate said type supporting members and print said information items in succession at said second printing rate,
  - (d) means responsive to partial completion of a cycle of operation of said translator for controlling said source-cycle control means to initiate a new cycle of operation of said cyclic source means,
  - (e) electrical storage means electrically controlled by said cyclic source means for storing during an interval following completion of each translator cycle the coded information item presented during said each translator cycle, and
  - (f) repeat-character means for coincidence sampling of the coded information item stored by said storage means and a coded information item newly presented by said cyclic source means to ascertain the identity, or the lack of identity, between the coded signals presented in respect each preceding and new translator cycle and
- (1) operative upon each ascertainment of such

- identity for controlling said cycle-control clutch and thereby said source-cycle control means temporarily to delay for a preselected interval utilization of the newly presented coded signals by said translator and the presentation of succeeding coded signals by said cyclic source means temporarily to reduce the repetitive operating rates of said translator and said cyclic source means from said second rate to said first rate,
- (2) said first rate being determined by said repeat character means and independent of the cycle operating rate of said translator cycle-control clutch, thereby enabling said second rate to be other than an integer multiple of said first rate.
6. A typewriter repeat-character-delay code translator system according to claim 5 wherein said electrical coded signals are comprised by electrical energizations of individual ones of a plurality of code electrical circuits providing permutational combinations of zero and one code bits in successive code-bit groups identifying said successively and cyclically presented coded alpha-numeric and symbol information items.
7. A typewriter repeat-character-delay code translator system according to claim 6 wherein said storage means is comprised by a multi-bit information-item storage register for individually storing the zero and one code bits identifying each information item successively presented for printing.
8. A typewriter repeat-character-delay code translator system according to claim 7 wherein said storage register is comprised by code bit bi-stable storage registers each operable between two states individually identified storage of zero and one code bits.
9. A typewriter repeat-character-delay code translator system according to claim 8 wherein said repeat-character control means includes:
- (a) means responsive to the code bits of a code-bit group newly presented to control each print cycle for coincidence sampling thereof with the corresponding code bits of a code-bit group stored by said storage register during the preceding print cycle and for essentially concurrently storing the code bits of the code-bit group newly presented, and further includes
  - (b) means responsive to each prevailing state of sampled coincidence identity between the code-bit group newly presented for control of each new print cycle and that identified by said storage register as having been presented for control of the immediately preceding print cycle to
- (1) utilize without delay the newly presented code-bit group in the absence of said coincidence identity, and
  - (2) to utilize with delay said newly presented code-bit group upon each occurrence of said coincidence identity and thereby effect said temporary reduction of the repetitive operating rate of said translator from said second rate to said first rate.
10. A typewriter repeat-character-delay code translator system according to claim 8 wherein said repeat-character control means includes:
- (a) electrical energy storage means, and
  - (b) includes means responsive to each group of code bits newly presented to control each new print cycle for coincidence sampling the operative states of said storage registers so to control energy storage in said energy storage means as to indicate a prevailing state of identity or lack thereof between said newly presented code-bit group and that stored by said storage register, and additionally includes
  - (c) means controlled by energy storage in said energy storage means indicative of said prevailing code-bit group identity or lack thereof for controlling said translator cycle-control clutch respectively to

(1) delay for said preselected interval, or to
 (2) effect without delay, the utilization of said
 newly presented code-bit group by said
 translator.

11. A typewriter repeat-character-delay code translator system according to claim 10 wherein

(a) said translator cycle-control clutch is controllable to halt said translator at a cyclic home position marking completion of each cycle of its operation, and
 (b) wherein said means controlled by energy storage in said energy storage means controls said translator cycle-control clutch to release said translator

(1) without delay past said home position thereof upon each lack of a prevailing state of identity between said newly presented code-bit group and that stored by said storage register, and
 (2) to release said translator with preselected delay past said home position thereof upon each occurrence of said prevailing code-bit group identity.

12. A typewriter repeat-character-delay code translator system according to claim 10 which includes timing means responsive to presentation of each new code-bit group for establishing said preselected delay interval value for said delayed utilization of said newly presented code-bit group.

13. A typewriter repeat-character-delay code translator system according to claim 12 in which said timing means includes

(a) a monostable multivibrator operative from a first to a second operative state thereof upon said presentation of said each new code-bit group with automatic timed return from said second to said first operative state thereof to establish said preselected delay interval value, and
 (b) means responsive to said return of said multivibrator from said second to said first operative state for controlling said translator cycle-control clutch to effect said delayed utilization of said newly presented code-bit group.

14. A typewriter repeat-character-delay code translator system according to claim 7 wherein said storage register is comprised by code bit magnetic storage devices each operable between two magnetic states individually identifying storage of zero and one code bits.

15. A typewriter repeat-character-delay code translator system according to claim 14 wherein said repeat-character means includes

(a) means responsive to each code-bit group newly presented to control each new print cycle for utilizing the one and zero code bits thereof to set corresponding individual ones of said storage devices to or maintain them in a respective first or a second magnetic state, and includes

(b) means responsive to each lack of change of the magnetic states of all of said storage devices upon each new code-bit group presentation for controlling said translator cycle-control means to effect said delayed utilization of said newly presented code-bit group.

16. A typewriter repeat-character-delay code translator system according to claim 14 wherein said repeat-character means includes

(a) means responsive to each code-bit group newly presented to control each new print cycle for
 (1) utilizing the one code bits thereof to set corresponding individual ones of said storage devices to or maintain them in one polarity of magnetic saturation, and for

(2) thereafter utilizing the zero code bits of said newly presented code-bit group to set corresponding individual ones of said devices or maintain them in a polarity of magnetic saturation opposite to said one polarity, and includes

(b) means responsive on the one hand to any change of setting of one of said magnetic storage devices between said one and opposite polarities and on the other hand to lack of change of setting of all of said devices for controlling said translator cycle-control clutch respectively to effect non-delayed and delayed utilization of said newly presented code-bit group.
